(57) **CLAIM**

The ornamental design for an electric vehicle, as shown and described.

DESCRIPTION

FIG. 1 is a front and right side perspective view of an electric vehicle;

FIG. 2 is a rear and right side perspective view thereof;

FIG. 3 is a front elevation view thereof;

FIG. 4 is a rear elevation view thereof;

FIG. 5 is a top plan view thereof;

FIG. 6 is a right side elevation view thereof; and,

FIG. 7 is a left side elevation view thereof.

The broken lines shown in the drawings illustrate portions of the electric vehicle that are environmental structures and form no part of the claimed design.
